J. L. WHITE & S. C. BAKER.

GREASE GUN.

APPLICATION FILED JULY 7, 1916.

1,268,654.

Patented June 4, 1918.

UNITED STATES PATENT OFFICE.

JAMES L. WHITE AND STUART C. BAKER, OF SOUTHAMPTON, NEW YORK.

GREASE-GUN.

1,268,654.

Specification of Letters Patent.

Patented June 4, 1918.

Application filed July 7, 1916. Serial No. 107,956.

To all whom it may concern:

Be it known that we, JAMES L. WHITE, and STUART C. BAKER, citizens of the United States, and residents of Southampton, in the county of Suffolk and State of New York, have invented certain new and useful Improvements in Grease-Guns, of which the following is a specification.

The present invention relates to lubricating and has particular reference to new and useful improvements in portable force feed lubricating devices commonly known as grease guns.

The primary object of our invention is to provide a force feed device for heavy lubricants, such as grease and the like, the device being arranged for transportation from place to place and having an outlet conduit for reaching difficult points in complicated machinery.

Another object of our invention is to provide a device of the character described which is simple in construction, light, strong and durable and effective in operation.

Another object of our invention is to provide a force feed lubricating device in which the parts thereof are adapted to be disassociated for cleaning and replenishing the container.

Other objects and advantages to be derived from the use of our improved force feed lubricating device will appear from the following detail description and the claim, taken with an inspection of the accompanying drawing, in which:

Figure 1 is a vertical sectional view of a force feed lubricator embodying the improvements of our invention; and

Fig. 2 is a fragmental sectional view of a connecting means.

Referring more particularly to the drawing, wherein similar characters of reference designate like and corresponding parts throughout the various views, 1 designates the base of our improved lubricating device, said base having a plurality of supporting legs 2 extending downwardly therefrom, the free ends of the legs being provided with feet 3.

The base 1 is provided, preferably at diametrically opposite points with a pair of enlargements 4 and 5 having the threaded portions 6 and 7 of vertical standards 8 and 9 engaged therein.

The upper free ends of the standards 8

and 9 are provided with annular shoulders 10 and 11 and heads 12 and 13. A transverse supporting frame 14 is provided constructed in the form of a truss, the free ends 60 of said frame 14 being provided with hook members 15 for engagement with the standards 8 and 9 between the respective collars and heads thereof. Set screws 16 and 17 serve to prevent displacement of the frame 65 when in use. A grease receptacle 18 having its upper edge flared as at 18' so as to engage the vertical standards 8 and 9 is mounted on the base 1, a plurality of lugs 19 being formed on said base to prevent displacement of said receptacle. An outlet 20 is formed in the receptacle 18 adjacent the bottom thereof, and a flexible conduit is connected at said outlet, to convey the lubricant to desired points. 75

The contents of the receptacle 18 are forced therefrom by means of a piston 21 formed with an annular flange 22 forming an engaging surface for snug movement in the receptacle 18. An actuating piston rod 80 23 is provided, said rod 23 being threaded and engaged in a threaded aperture 24 formed in the truss or frame 14. A transverse handle 25 is carried by the upper end of the piston rod 23 for rotating said piston 85 rod. The lower free end of the rod 23 is rotatably engaged with the piston as indicated at 26.

It will be seen that in using our improved grease gun the same may be transported 90 from place to place, the flexible conduit serving to convey the contents of the receptacle 18 to the remote parts of the machine. The frame 14 may be quickly removed by loosening the screws 16 and 17, and the standards 8 and 9 may also be quickly removed from the base. Thus it will be seen that in the provision of our improved grease gun we afford means for distributing a lubricant to desirable points, the device of our 100 invention permitting the application of the lubricant to parts which would ordinarily be inaccessible, or would cause considerable difficulty to reach.

From the above description taken in connection with the accompanying drawing, it is thought that a clear and comprehensive understanding of the construction, operation and advantages of our invention may be had, and while we have shown and described the device as embodying a specific structure, we desire that it be understood 105 110

that such changes may be made in said structure as do not depart from the spirit and scope of the invention as claimed.

Having thus fully described our invention, what we claim as new and desire to secure by Letters Patent, is:—

A grease gun including a base, a pair of diametrically opposed upstanding enlargements on the marginal edge of said base, 10 said enlargements having threaded openings therein, upstanding lugs on the edge of said base, a receptacle mounted on the base and held in position by said lugs and enlargements, said receptacle having an outlet therein adjacent its bottom, a pair of standards having their lower ends threaded for engagement with the enlargements, an

outwardly flared upper edge on said receptacle engaging the standards to steady the receptacle, annular shoulders formed on the standards adjacent their free ends, head portions formed on the free ends, a transverse supporting frame, hook members formed on the ends of the supporting frame adapted to detachably engage the standards between said heads and shoulders, a piston mounted within said receptacle, and means associated with the piston and supporting frame to actuate the same.

In testimony whereof, we affix our signatures hereto:

JAMES L. WHITE.
STUART C. BAKER.

Copies of this patent may be obtained for five cents each, by addressing the "Commissioner of Patents, Washington, D. C."
